UNITED STATES PATENT OFFICE

2,426,717

COMBINATION HOIST AND JACK

John J. Uhlenkott, Downieville, Calif.

Application December 27, 1944, Serial No. 569,982

1 Claim. (Cl. 254—100)

1

This invention relates to a combination hoist and jack, and has as its primary object the provision of an improved device which may be interchangeably utilized to push or pull loads.

An additional object of this invention is the provision of such device having a screw-threaded means associated therewith which may be readily turned in either direction to either lengthen or shorten the jack against the pressure of a heavy load.

A more specific object of the invention is the provision of such device which will so act as to preclude slippage of a jack per se when so operated.

Still another object is the provision of improved pusher plates in association with such a jack, which may be readily altered to provide hoisting hooks as desired.

Still another object is the provision of such a device which will be sturdy and durable in construction, reliable and efficient in operation, and relatively simple and inexpensive to manufacture and operate.

Other objects reside in the combinations of elements, arrangements of parts, and features of construction, all as will be more fully pointed out hereinafter and shown in the accompanying drawings, wherein there is disclosed a preferred embodiment of this inventive concept.

In the drawings:

Figure 1 is a side elevational view of one form of jack embodying this invention.

Figure 2 is a side elevational view of the device shown in Figure 1, certain parts thereof being shown in different positions of adjustment.

Figure 3 is a top plan view of the device shown in Figure 1.

Figure 4 is an enlarged sectional view taken substantially along the line 4—4 of Figure 3.

Figure 5 is an enlarged perspective view of a constructional detail, and

Figure 6 is an enlarged plan view of one of the operating elements of the device.

Like reference numerals refer to like parts throughout the several views of the drawings.

Having reference now to the drawings, 10 designates a threaded rod or screw, surrounding one end of which is a sleeve 11 having secured thereto two frame or brace members 12 and 13, which extend to and are secured to a second sleeve 14 in longitudinal alignment but spaced from the sleeve 11. A collar 15, secured as by an extending lug 16 to frame member 13, surrounds a portion of a thrust bearing 17 abutting the end of sleeve 11 and similarly positioned ad-

2

jacent the end of sleeve 14 is a second thrust bearing 18. Positioned between collar 15 and thrust bearing 18 is a bevel gear 19 having a threaded interior bore threadedly engaging the threads of rod 10. Thrust bearings 17 and 18 carry anti-friction or ball bearings as shown to take up end thrust on the sleeves 11 and 14 and keep pressure off of the gear 19. Journalized in frame or brace member 12 and collar 15 in engagement with bevel gear 19 is a second bevel gear 20 having an extending shaft 21. The end of shank 21 is adapted to be engaged by a reversible ratchet handle generally indicated at 25 (see Fig. 6), including a head 26, a handle 27 and a reverse button 28. Ratchet handle 25 may be of conventional design and include a conventional ratchet 30 and spring-pressed pawl 31 (see Fig. 4).

From the foregoing it will now be seen that 20 as the ratchet handle 25 is moved, bevel gear 20 moves bevel gear 19 which in turn, through its threaded engagement with rod 10, causes the same to move within the sleeves 11 and 14.

Secured to one end of sleeve 11 is a load engaging member generally indicated at 35 comprising a combined push plate 36 and a hook 37. Plate 36 is split to form bifurcations 38 and 39 and provided with spaced downwardly extending flanges 40 and 41 having pairs of apertures 42 passed in aligned relation therethrough. A pivot 43 secures the members in pivotal relation to sleeve 11. The hooks 37 are pivoted at the other aligned apertures 42.

An identical member 35 is attached at the 35 outer end of sleeve 14 to rod 10, as by a pivot 44.

Now, from the foregoing it will be seen that when the ratchet member 25 is moved in one direction and the members 35 are positioned as shown in Figure 1, that is, with their push faces outwardly, the rod 10 will move outwardly with respect to its associated sleeve and exert a pressing action as a jack. Conversely, it will be seen that when the members are in the positions shown in Figure 2, that is to say, with the hooks 37 positioned outwardly on the pivots 43 and 44 with the heads or plates 36 turned down against the sides of the sleeves 11 and 14, and the rod 10 extended with respect to its associated sleeve, 50 a reverse ratchet action by member 25 will cause the members to contract and thus effect a contracting lifting or hoist action.

From the foregoing it will be seen that there is herein provided a device accomplishing all the 55 objects of this invention and others, including

many advantages of great practical utility and commercial importance.

As many embodiments may be made of this inventive concept, and as many modifications may be made in the embodiment hereinbefore shown and described, it is to be understood that all matter herein is to be interpreted merely as illustrative and not in a limiting sense.

I claim:

In a combination hoist and jack, a screw, a bevel gear having an interiorly threaded bore mounted on said screw, sleeves surrounding and rotatably mounting said screw on opposite sides of said gear, end thrust bearings between the inner ends of said sleeves and said gear, brace members connected to said sleeves on opposite sides thereof and straddling said gear and thrust bearings, a collar secured to one brace member and surrounding the screw between the thrust bearings, a second bevel gear rotatably mounted in the other brace member and said collar and

disposed in mesh with the first gear, means for rotating said second bevel gear in either direction, and push plates pivoted to the outer end of one sleeve and the opposite end of the screw and provided with a hook at one end of each, said plates being adapted to be disposed crosswise or longitudinally against the sides of the sleeves with the hooks extending outwardly for pushing or pulling loads.

JOHN J. UHLENKOTT.
